UNITED STATES PATENT OFFICE.

FRANK W. BRYANT, OF WEST LAFAYETTE, INDIANA, ASSIGNOR TO THE PHI KAPPA TAU FRATERNITY, OF INDIANAPOLIS, INDIANA, A CORPORATION OF OHIO.

DESIGN FOR A FRATERNITY BADGE.

Application filed March 11, 1927. Serial No. 21,112. Term of patent 14 years.

To all whom it may concern:

Be it known that I, FRANK W. BRYANT, a citizen of the United States, residing at West Lafayette, in the county of Tippecanoe and State of Indiana, have invented a new, original, and ornamental Design for a Fraternity Badge (Case 1), of which the following is a specification, reference being had to the accompanying drawing, forming a part thereof.

I claim:—

The ornamental design for a fraternity badge as shown.

In testimony whereof I affix my signature.

FRANK W. BRYANT.
